UNITED STATES PATENT OFFICE.

HERBERT E. WEEGHMAN, OF CHICAGO, ILLINOIS.

DESIGN FOR A FRONT PLATE OF VENDING APPARATUS.

51,052.

Specification for Design.

Patented July 17, 1917.

Application filed May 28, 1917. Serial No. 171,596. Term of patent 7 years.

To all whom it may concern:

Be it known that I, HERBERT E. WEEGHMAN, a citizen of the United States, residing at Chicago, in the county of Cook and State of Illinois, have invented a new, original, and ornamental Design for Front Plates of Vending Apparatus, of which the following is a specification, reference being had to the accompanying drawing, forming part thereof.

In the drawing:

Figure 1 is a front elevation of the plate, and

Fig. 2 is an edge view of the same.

I claim:

The ornamental design for a front plate of vending apparatus, substantially as shown.

HERBERT E. WEEGHMAN.
